E. M. Bentley

UNITED STATES PATENT OFFICE

ROBERT J. PARSONS, OF SCHENECTADY, NEW YORK, ASSIGNOR, BY MESNE ASSIGNMENTS, TO CONSOLIDATED CAR-HEATING COMPANY, INC., OF ALBANY, NEW YORK, A CORPORATION OF NEW YORK

ELECTRIC DOOR-MOTOR

Application filed August 17, 1926. Serial No. 129,829.

For a detailed description of the present form of my invention, reference may be had to the following specification and to the accompanying drawings forming a part thereof, wherein

Fig. 1 is a plan partly in section of my device;

Fig. 2 is a front view of the switch box with the cover removed and

Fig. 3 is a diagram of the circuits.

My invention relates to electric door operators wherein an electric motor is arranged to reciprocate a car-door, or any door requiring similar movement.

Referring to Fig. 1 E represents an electric motor having its casing connected to a gear-box J and a switch-box F. The armature shaft of the motor carries a spur-pinion 20 which drives a gear-wheel 21 on the shaft 20 of which is a second pinion 22 that drives a gear-wheel 23, and on the shaft of said gear-wheel 23 is a third pinion 24 that drives gear-wheel 25 on the door-arm shaft D. The door-arm is shown at G and, in a manner now well known and requiring no illustration, operates the door back and forth by a movement over an arc of approximately 180 degrees, a roller on the outer end of the arm engaging a vertical guideway on the rear edge of the door. The door-arm shaft D enters the switch-box F and, as appears in Fig. 2, carries two cams H and K which, for convenience of illustration, are shown separately in the figure, one above the other, although it is to be understood that in practice the two cams are placed side by side on the common shaft D, each acting on its individual set of switches. The cam H acts alternately on the levers P and Q while cam K acts alternately on the levers S and R. The lever Q operates the spring-pressed switch X that opens and closes the connection between contacts 11 and 12, while lever P operates the similar switch Y which opens and closes the connection between contacts 13 and 14. The cam H is shown in its midway position both switches being open. In a similar way the cam K controls the closure of the connections between contacts 9 and 10 of switch V on the one

hand and contacts 15 and 16 of switch W on the other hand.

The cam H is longer in a circumferential direction than cam K, and, therefore, as it moves to one side or the other, will operate switch X or Y before cam K operates switch V or W.

In operation we may assume that the motor is propelling the door towards its closed position and shaft D with cams H and K is rotating in an anti-clockwise direction, having reference to Fig. 2. As the door approaches the closed position the first effect will be the closing of switch X by the action of cam H on lever Q. The result of this may be seen by reference to the circuit diagram of Fig. 3. This assumed door-closing direction of the motor movement has been established by moving the manual control-switch A² to the left, thereby connecting contacts 1 and 5, also contacts 2 and 6 of that switch, while the contacts 9 and 10 of switch V (which is the door-closing limit switch) are as yet unopened. Thereby the current will pass from trolley T, to contacts 6 and 2, to contacts 10 and 9, to field-magnet A of the motor, to motor armature C and to ground. The field-magnet coil A is so wound as to give the motor its desired door-closing direction, the other field-magnet coil B, (now inactive), being the one that gives the opposite or door-opening direction. This being the situation, the switch X is now closed, as aforesaid, by cam H and lever Q. That will establish a new circuit from the armature end of field-magnet coil A, through field-magnet coil B (in a direction opposite to the normal door-opening current of that coil—namely, in a direction to cause a co-operation of field-magnet coils A and B to close the door), thence to contacts 5 and 1 of the control-switch, to contacts 12 and 11, now closed, of switch X, and to ground. By the aforesaid closure of switch X three effects are produced: (1) the cooperative connection aforesaid of field-coils A and B, (2) the voltage applied to armature C is reduced (3) the voltage applied to field-coil A is increased. As a result the motor speed is reduced, but the motor torque is maintained, or even in-

creased. The reduction in motor speed is due to the stronger field magnet and the reduced voltage applied to its armature—not to a weakening of its torque. Thereby the 5 motor is enabled to complete the run of the door because of its maintained torque, although its speed is reduced preparatory to its stopping. Consequently the motor slows down as it approaches the end of its run, and 10 the inertia of its high-speed armature, which has such a large gearing ratio with respect to the comparatively slow-moving door, is brought under control initially prior to the actuation of the limit-switch. Following 15 the operation of switch X, as just described, by the cam H, comes the operation of limit-switch V by cam K and lever S. That interrupts the flow of current from trolley T to the motor-coils, but there still remains a 20 closed circuit for the motor armature C, from ground on one side of it, through the armature itself, and thence through field-coil B, control-switch contacts 5 and 1, contacts 12 and 11 of switch X and back to ground. 25 This puts a final brake-effect on the motor which now acts as a short-circuited generator and brings it to rest. The action is the same for the opposite direction of movement of the door and motor, the switches Y and W being 30 then operated in succession with the same effect as the aforesaid switches X and V. In each case the motor is first automatically weakened and its limit-switch then opened in a way to give a braking effect to bring it 35 mechanically to a stop.

It will be noted that while field-magnet coil B, when acting alone, will have an effect which is the reverse of the corresponding coil A when acting alone, yet when switch X is 40 closed, as above described, both coils will be energized to give the same direction of rotation and will therefore supplement each other. The two coils when thus supplementing each other will double the effect of A or 45 B when acting alone. In addition, the drop in voltage thereby applied to the armature will increase somewhat the voltage applied to coil A because the line voltage remains unchanged. Therefore the field-magnet effect 50 is more than doubled when the two field-magnet coils thus supplement each other. After the aforesaid closure of switch X, which inauguates the first slowing-down stage or period, the limit switch V is opened and there- 55 by the current supply is cut off. This inauguates the second slowing-down stage or period. The motor then begins to act as a generator and the stopping effect of that action is maintained until the door and motor stop. 60 While I do not now know of any motor other than a door motor with its door geared there- 65 to that would call for my braking or stopping device, yet it will be understood that the door shaft mentioned in the following claims includes any equivalent shaft requir-

ing the same operative treatment as the shaft D of my above described apparatus.

What I claim as new and desire to secure by Letters Patent is:

1. The combination with a door shaft, of 70 a driving motor connected thereto and stopping therewith, said motor including an armature and oppositely wound field magnets so that the motor may be operated in either direction, a supply circuit for said motor, a normally closed limit switch controlling said circuit and one of said field magnets, means for opening said switch at a predetermined time during the operation of said door shaft, a normally open field magnet switch, means for operating the field magnet switch in advance of the operation of said limit switch, and means associated with said field magnet switch for connecting said field magnets in series with each other so as to reduce the 80 voltage supply to said armature.

2. The combination with a door shaft, of 85 a driving motor connected thereto and stopping therewith, said motor including an armature and two field magnet coils connected respectively for opposite directions of armature rotation, a supply circuit for said motor, and an automatic controller for said motor comprising two sets of switches, each set including a limit switch for controlling the motor circuit and one of said field magnet coils, means for operating said switch to open the motor supply circuit at a predetermined time during the operation of said door shaft, a field magnet switch acting in advance of said 90 limit switch, and means associated with said limit switch to connect the inactive field magnet coil to the supply and to reduce the voltage supplied to said armature.

3. The combination with a door shaft, of 95 a driving motor connected thereto and stopping therewith, said motor including an armature and oppositely wound field magnets so that the motor may be operated in either direction, a supply circuit for said 100 motor, a manual reversing switch for said motor, and an automatic controller in series with said manual switch, said controller including a normally closed limit switch controlling said circuit and one of said field magnets, means for opening said switch at a predetermined time during the operation of the door shaft, a normally open field magnet switch, means for operating the field magnet switch in advance of the operation of said 105 limit switch, and means associated with said field magnet switch for connecting the inactive field magnet coil to the motor supply circuit and to reduce the voltage supplied to said 110 armature.

4. The combination with a door shaft, of 115 a driving motor connected thereto and stopping therewith, said motor including an armature and two field magnet coils arranged for opposite directions of armature 120

125

130

- rotation, a supply circuit for said motor, a manual reversing switch, and an automatic controller including a limit switch controlling said motor circuit and one of said field magnets, a field magnet switch, means associated with said field magnet switch for connecting the inactive field magnet coil to said motor supply circuit so as to reduce the voltage supply on said armature, and cams mounted on said shaft and positioned to engage and operate the respective switches, the cam for operating said field magnet switch being positioned to actuate the same in advance of the operation of said limit switch.
- 5 5. The combination with a door shaft, of a driving motor connected thereto and stopping therewith, said motor including an armature and oppositely wound field magnets so that the motor may be operated in either direction, a supply circuit for said motor, a manual switch having two sets of contacts, means associated with one set of contacts for selectively connecting said circuit to the ground or through one of said field magnets and the armature, said means including a normally closed limit switch, and means for automatically opening said switch at a predetermined time during the operation of said shaft, means associated with the other set of contacts for connecting the last mentioned field magnet to ground through the other field magnet, said means including a normally open switch, and means for automatically closing the last mentioned switch in advance of the opening of said limit switch so as to reduce the voltage supplied to said armature.
- 10 6. The combination with an electric motor having two field magnets arranged for opposite directions of motor rotation, and an armature having a terminal connection with both coils at a position intermediate between them, a limit switch normally biased to circuit closed position and controlling the circuit through one of said coils, a ground connection around said armature and including the other coil, a voltage switch controlling the ground connection, said voltage switch being normally biased to open circuit position, a control switch provided with contacts for establishing circuit to the motor through the limit switch and through the voltage switch respectively, a shaft rotatably actuated by said motor and having cams, and means interposed between said cams and said switches for effecting operation of the switches during rotation of said shaft, said cams being positioned to operate the switches in a predetermined sequence.
- 15 60 Signed at Albany, county of Albany, State of New York, this 6th day of Aug., 1926.

ROBERT J. PARSONS.
